UNITED STATES PATENT OFFICE

ELMER L. SMITH, OF LONGMEADOW, MASSACHUSETTS, ASSIGNOR TO PACKAGE MACHINERY COMPANY, OF SPRINGFIELD, MASSACHUSETTS, A CORPORATION OF MASSACHUSETTS

METHOD OF APPLYING LABELS TO PACKAGES

Application filed March 17, 1928. Serial No. 282,509.

The present invention relates to the art of wrapping articles. It has for its object the production of a novel type of package in which printed labels are affixed to an underlying wrapper of waxed paper, and a process by which it is, for the first time, possible to form such a package.

It has been common in certain lines of merchandise to wrap the articles in a printed paper, and to place on the ends of the package, whereby reason of the folds the printed wrapper is not a good medium for displaying the desired trade-marks or information, a printed label glued in place across the end folds. With merchandise subject to deterioration unless protected from changes in moisture content, it has also been common to surround the articles with a wax paper covering stuck together by heat sealing. Over the body of the package this wax paper covering is sufficiently transparent to display the printing underneath, but at the ends of the package the necessary folds, resulting in creases and in additional thickness, have destroyed the transparency to such a degree that end labels were made practically illegible when applied to the package underneath.

Previous attempts to apply end labels over the wax paper have not been successful, as ordinary methods of attachment fail to produce adhesion. The use of wax as an adhesive renders the application easy, but the adhesion is not permanent and a prohibitive proportion of the labels peel off. Glue or paste applied in the ordinary manner will not stick to wax paper and, therefore, have not been used. I have found that by a special procedure it is possible to employ the usual adhesives, which produce a permanent union 40 with the underlying paper.

Referring to the drawings:

Fig. 1 is a perspective view of a package with a wax paper wrapping thereon;

Fig. 2 is a plan view of the package illustrating the method of sealing the ends of the wax paper and preparing it for the application of an end label;

Figs. 3 and 4 are plan views illustrating the manner of application of the adhesive 50 coated label; and

Fig. 5 is a plan view illustrating a modified procedure.

The package 10 is shown in Fig. 1 as covered with a layer of wax paper having folds 11, 12 at the ends. The particular manner of folding is immaterial. In order to seal these folds together it is customary to pass the end of the package in contact with a shoe 13 having a heating element 14 embedded therein. As the paper passes the shoe the wax 60 in the end folds becomes melted and fuses together. According to my invention I utilize this sealing operation to condition the wax paper for the application of the label.

I have found that if a label coated with adhesive is rolled into contact with the package end while the wax is softened, it will press the wax out of the way and bring the adhesive into contact with the underlying paper. In Figs. 3 and 4 I have shown the label, with the 70 side which is to be in contact with the package coated with adhesive, supported on a rocker 16 serving to press the label by rolling contact against the package end. Various mechanisms may be used for this purpose, as 75 for example the label applying device shown in my prior Patent No. 1,575,723, granted March 9, 1926.

Any good adhesive may be used upon the label, as the primary mode in which my invention operates appears to be the pressing of the wax out of the way so that the adhesive may make direct contact with the underlying paper. It is, however, preferable to use an adhesive such as Ceresol, which 85 has inherent adhesion for wax as well as for paper. In either case, however, I believe the main bond to be between the adhesive and paper.

As a further means of assisting the rolling away of the wax, I have found that moistening the wax, either before or after heating, with a solvent such as carbon tetrachloride will further increase adhesion if this is found necessary. In Fig. 5 I have shown a wick 18 95 mounted in a container 19 in position to apply the solvent after the package has passed the heat sealer 13, although the relative positions of the two devices may be reversed.

What I claim is:

1. A method of applying a label to a wax paper package which comprises softening the wax, and rolling an adhesive coated label against the softened area.
- 5 2. A method of applying a label to a wax paper package which comprises fusing the wax and rolling an adhesive-coated label against the area of fusion.
- 10 3. A method of applying a label to a wax paper package which comprises fusing the wax and rolling an adhesive coated label against the area of fusion with sufficient pressure to force away the fused wax and bring the adhesive in direct contact with the underlying paper.
- 15 4. A method of applying a label to a wax paper package which comprises subjecting an area of the wax to fusion and the action of a solvent, and rolling an adhesive coated label against the softened area with sufficient pressure to force away the softened wax and bring the adhesive in direct contact with the underlying paper.
- 20 5. A method of applying a label to a wax paper package which comprises heating the overlying folds of the wax paper to seal them together, and while the wax is still soft from this heat rolling an adhesive-coated label against the heated area with sufficient pressure to force away the fused wax and bring the adhesive in direct contact with the underlying paper.

In testimony whereof I have affixed my signature.

ELMER L. SMITH.
